Primary Examiner—Ted Shooman*Assistant Examiner*—Mitchell I. Siegel*Attorney, Agent, or Firm*—Richard B. O'Planick; Lisa B. Riedesel[57] **CLAIM**

The ornamental design for a playground activity apparatus, as shown and described.

DESCRIPTION

FIG. 1 is a top right front perspective view of a playground activity apparatus showing our new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof; and,

FIG. 7 is a bottom plan view thereof.

The broken line showing of a swing set is for illustrative purposes only and forms no part of the claimed design.
